UNITED STATES PATENT OFFICE.

RUDOLF KRAUS, OF LONG ISLAND CITY, NEW YORK, ASSIGNOR OF THREE-TWENTIETHS TO FRANZ BERGMANN, OF SAME PLACE.

AUTOMATIC MATCH-LIGHTER.

SPECIFICATION forming part of Letters Patent No. 491,314, dated February 7, 1893.

Application filed August 20, 1892. Serial No. 443,579. (No model.)

To all whom it may concern:

Be it known that I, RUDOLF KRAUS, of Long Island City, Queens county, New York, have invented an Improved Automatic Match-Lighter, of which the following is a specification.

This invention relates to a machine for automatically feeding and striking a match by the turn of a hand lever.

10 The machine is designed for use in stores and bar rooms, where the customer can thus be easily and neatly served with a lighted match.

15 The invention consists in the various features of improvement more fully pointed out in the claims.

In the accompanying drawings: Figure 1 is a top view of the machine. Fig. 2 is a longitudinal section on line x, x , Fig. 1. Fig. 3 a section on line y, y , Fig. 1. Fig. 4 a section on line z, z , Fig. 1. Fig. 5 a section on line x', x' , Fig. 1. Fig. 6 a section of part of the machine showing the jaws in a different position. Fig. 7 a cross section on line $y' y'$, Fig. 2. Figs. 8 and 9 longitudinal section of box d , showing the shelf closed and open and Fig. 10 a detail edge view of part of wheel j .

The letter a , represents the frame of the machine in which turns a rock shaft b , provided with an operating handle b' . Upon rock shaft b , is mounted the loose gear wheel b^3 . To the shaft b , are furthermore secured a pair of arms or hangers b^4, b^5 , connected at their lower ends by a bar b^6 , parallel to the shaft. To the arm b^5 , there is secured a click b^7 , that engages and revolves wheel b^3 , when the shaft b , is rocked forward but does not act upon the wheel when the shaft is rocked backward. Across the frame a , and parallel to the shaft b , there is hung a second shaft c , upon which are mounted two jaws c' , provided at their ends with the spring finger c^2 , made of unequal length. Upon the shaft c , there is rigidly mounted a gear wheel c^3 , meshing into wheel b^3 , and by which motion is imparted to the shaft c , when the shaft b , is rocked forward, while no motion is imparted to the shaft c , when the shaft b , is rocked backward.

50 d , is a box or a hopper for receiving the

matches. It is supported upon its rear end only by springs d' , that connect it to a bracket d^2 . At the front end the box d , is provided with a slit or discharge opening d^3 , a short distance above its bottom. To the bottom of the box d , is pivoted an inclined gate or shelf d^4 , acted upon by spring d^5 , and provided with a shoulder d^6 , back of slit d^3 . In front of the shelf d^4 , there is secured to the machine frame, a fixed inclined slide e . This slide is provided with a pair of slits through which project upwardly a pair of pivoted stops e' , that are weighted at their lower ends so as to become automatically righted.

Upon the shaft c , there is mounted a star wheel c^4 , which I term the "shaker" and which on the revolution of the shaft strikes against an arm d^7 , of box d , to rapidly vibrate the same on its spring d^8 .

To the shaft b , are attached a pair of fingers b^8 , that strike against pins d^7 , projecting laterally from shelf d^4 , when the shaft is rocked backward. Thus the shelf is opened and permits a match to drop down upon the slide e , and against the stops e' , while the shoulder d^6 , hold the other matches back. When the shaft b , is revolved forward the fingers b^8 , will release the pins d^7 , and the shelf will be closed by spring d^8 . The forward motion of shaft b , will also cause the shaft c , to be revolved a semi-revolution, it being understood that one complete motion of the hand lever produces a semi-revolution of the shafts b, c . The backward motion of the shaft c , will effect two objects, firstly it will by star wheel c^4 , rattle the box and thus shake a new match through slit d^3 , and upon the shelf d^4 , ready for the next operation. Secondly, it will cause the fingers c^2 , of the revolving jaw c' , to pick up the match that lies against the stops e' , and to carry it over the stops which will be tilted by the match. As the match f , descends the inclined slide e , it will be firmly pressed in between the spring fingers c^2 , and will be carried by the same into a position directly below the shaft c . In this position the match is held while the shaft b , turns backward because as has already been stated, the shaft c , remains stationary during the backward motion of shaft b . Upon the

next forward motion of shaft b , the match held by the spring fingers will be carried upward to lay vertically above shaft c , while a new match is picked up by the other pair of 5 spring fingers in the manner previously described. The first match in its upward motion will rub against a yielding abrading surface g , and become ignited. Thus it will be seen that each complete motion of the 10 machine presents one ignited match to the operator and picks up a second match which is ignited by the next operation. To keep the abrading surface clean I employ a scraper g' , fast on one of the jaws c' .

15 In order to lock the shaft c , in position during the backward motion of shaft b , I employ a catch or spring hook h , that is adapted to engage a perforation b^9 , of wheel c^3 , when the jaws c' , are in their terminal or vertical positions. This engagement is broken by finger h' , on shaft b , that throws the hook away from the wheel when the shaft b , has almost completed its backward motion.

Upon the shaft c , there is also mounted a 25 wheel i , having a pair of shoulders i' , placed diametrically opposite each other. These shoulders are adapted to be engaged by an arm i^2 , at each complete operation of the machine. The object of this arrangement is to 30 cause the shaft to perform always a full semi-revolution and bring a pair of jaws always properly to the top.

To prevent the shaft b , from falling back suddenly upon the release of the handle, I 35 connect it to a vane or fly j , by gear wheel j' , pinion j^2 , and gear wheel j^3 . The gear wheel j' , is fast on the shaft b , and engaged by a pawl j^4 , adapted to drop into either one of a pair of inclined notches j^5 , of wheel j' , when 40 the lever has arrived at its most forward position. This has for its object to prevent the shaft b , from being revolved backward unless a full forward motion has been imparted to the lever, in as much as the pawl will slip out 45 of the beveled notch j^5 , of wheel j' , but not out of the teeth of said wheel. When the handle is released, the shaft b , is rocked backward by a spring m , engaging the bar b^6 , which presses the bar forward and consequently 50 rocks the shaft b , backward. The backward motion of the shaft will be imparted to the handle, which will drop down gently under the influence of the fly wheel j , as already stated.

55 If desired, a sliding knife k , may be employed to cut off the tip of the cigar introduced through a perforation k' . This knife is oper-

ated by a suitable lever k^2 , acted upon by a pin k^3 , on bar b^6 . When the handle b' , is thrown forward the knife will be raised to cut off the 60 tip. But when the handle falls backward, a spring k^4 , acting upon lever k^2 , will cause the knife to descend below the perforation k' .

What I claim is,

1. The combination of a revolving shaft 65 with a pair of jaws secured thereto, a vibrating hopper, a pivoted stop between the hopper and the jaws and with a rubbing surface, substantially as specified.

2. The combination of a revolving shaft 70 with a pair of jaws having spring fingers and with a vibrating hopper, a pivoted gate controlling its discharge orifice, a stop and a rubbing surface, substantially as specified.

3. The combination of a shaft with a pair of 75 jaws, a hopper, springs supporting the same, a star wheel for agitating the hopper, a shelf controlling the discharge orifice of the hopper and with a rubbing surface, substantially as specified.

4. The combination of a shaft b , with inter- 80 geared shaft c , jaws c' , secured thereto and having fingers c^2 , and with hopper d , shelf d^4 , inclined slide e , stop e' , and rubbing surface g , substantially as specified.

5. The combination of shaft b , having hand lever b' , and loose wheel b^3 , with shaft c , having jaws c' , and adapted to be intergeared with shaft b , and with a hopper, a pivoted shelf, a slide, a stop and a rubbing surface, 90 substantially as specified.

6. The combination of shaft b , with inter- 95 geared shaft c , having jaws c' , wheel i , having shoulders i' , and an arm i^2 , adapted to engage such shoulders, substantially as specified.

7. The combination of shaft b , with inter- 100 geared shaft c , having jaws c' , and with a hopper, a pivoted stop, a rubbing surface and with a knife k , operated by the shaft b , substantially as specified.

8. The combination of shaft b , with notched gear wheel j' , pawl j^4 , a fly j , and with a shaft c , having jaws c' , a hopper, a stop and a rubbing surface, substantially as specified.

9. The combination of a shaft c , with a pair 105 of jaws c' , a vibrating hopper, a pivoted gate having a shoulder d^6 , and controlling the discharge orifice of the hopper and with a stop between the hopper and the jaws, substantially as specified.

RUDOLF KRAUS.
